[57] **CLAIM**

The ornamental design for a wall lantern, as shown and described.

DESCRIPTION

FIG. 1 is a front perspective view of a wall lantern showing my new design;

FIG. 2 is a left side elevational view of the wall lantern, the right side elevational view being a mirror image;

FIG. 3 is a front elevational view of the wall lantern;

FIG. 4 is a rear elevation view of the wall lantern;

FIG. 5 is a top plan view of the wall lantern; and,

FIG. 6 is a bottom plan view of the wall lantern.

The broken lines are shown for illustrative purposes and form no part of the claimed design.
